UNITED STATES PATENT OFFICE.

JOHN E. ALLEN, OF BIG CREEK, CALIFORNIA.

DESIGN FOR AN AUTOMOBILE-BODY.

59,318.

Specification for Design.

Patented Oct. 11, 1921.

Application filed May 17, 1921. Serial No. 470,481. Term of patent 7 years.

To all whom it may concern:

Be it known that I, JOHN E. ALLEN, a citizen of Canada, residing at Big Creek, in the county of Fresno and State of California, have invented a new, original, and ornamental Design for Automobile-Bodies, of which the following is a specification, reference being had to the accompanying drawings, forming part thereof.

Figure 1 is a top plan view.

Fig. 2 is a side elevation.

I claim:

The ornamental design for an automobile body, substantially as shown.

JOHN E. ALLEN.
